UNITED STATES PATENT OFFICE

123,294

DESIGN FOR A COMBINATION DESK- CALENDAR UNIT

William H. Kemp, Westfield, N. J., assignor to Ever Ready Calendar Manufacturing Co., Jersey
City, N. J., a corporation of New Jersey

Application August 26, 1940, Serial No. 94,635

Term of patent 7 years

To all whom it may concern:

Be it known that I, William H. Kemp, a citizen of the United States, residing in Westfield, Union County, New Jersey, have invented a new, original, and ornamental Design for a Combination Desk-Calendar Unit, of which the following is a specification, reference being had to the accompanying drawing, forming a part thereof, in which:

Fig. 1 is a front perspective view of a combination desk-calendar unit showing my new design; and

Fig. 2 is a rear perspective view thereof.

I claim:

The ornamental design for a combination desk-calendar unit, as shown.

WILLIAM H. KEMP.
